(57) **CLAIM**

The ornamental design for a force sensor, as shown and described.

DESCRIPTION

FIG. 1. is a perspective view of a new design for a force sensor;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The portions displayed by broken lines in the figures do not represent part of the claimed design.
